UNITED STATES PATENT OFFICE

110,385

DESIGN FOR AN ADVERTISING DEVICE

Walter D. Brookings, Jr., Alexandria, Va.

Application April 14, 1938, Serial No. 76,504

Term of patent 14 years

To all whom it may concern:

Be it known that I, Walter D. Brookings, Jr., a citizen of the United States, residing in the city of Alexandria, State of Virginia, and whose post office address is Menokin, Seminary Hill, in said city, have invented a new, original, and ornamental Design for an Advertising Device, of which the following is a specification, reference being had to the accompanying drawing, constituting a part thereof.

In the drawing:

Figure 1 is a side view of an advertising device embodying the design;

Figure 2 is a rear view of the device; and
Figure 3 is a front view of the device.

I claim:

The ornamental design for an advertising device substantially as shown.
